[57] CLAIM

The ornamental design for an overload current switch,
as shown and described.

DESCRIPTION

FIG. 1 is a top, front and left perspective view of a first
embodiment of an overload current switch showing our
new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a top, front and left perspective view of a
second embodiment of an overload current switch
showing our new design;

FIG. 9 is a left side elevational view thereof;

FIG. 10 is a right side elevational view thereof;

FIG. 11 is a front elevational view thereof;

FIG. 12 is a rear elevational view thereof;

FIG. 13 is a top plan view thereof; and,

FIG. 14 is a bottom plan view thereof.

The broken line showing in FIGS. 7 and 14 is included
for the purpose of illustrating environmental structure
only and forms no part of the claimed design.
